HERBERT C. M. STEVENS, OF PARIS, FRANCE, AND ROLAND V. HUTCHINSON, OF LANSING, MICHIGAN, ASSIGNEES TO GENERAL MOTORS CORPORATION, OF DETROIT, MICHIGAN, A CORPORATION OF DELAWARE

CRANK-CASE VENTILATION

Application filed October 10, 1927. Serial No. 225,216.

This invention relates to crankcase ventilation and has to do particularly with the crankcase ventilating system for an internal combustion engine of an automotive vehicle.

It is well known that fouling of the crankcase results from the escape of the products of the combustion chamber between the piston and cylinder walls into the crankcase. It is an object of the present invention to remove the escaped gases through the walls of the crankcase just below the lowest position of the lower edge of the piston and before they have become mixed with the crankcase lubricant. It is a further object of the invention to provide such a ventilating system which will be operated by the suction of the intake manifold. The particular advantages of this arrangement are that there will always be suction to operate the ventilating system when the engine is running and the ventilating current of air will be disposed of by being passed through the combustion chambers of the engine.

Other objects and advantages of the invention will appear in the course of the following description, taken in connection with the accompanying drawings and appended claims.

In the drawings:

Figure 1 is a transverse vertical section of an internal combustion engine embodying our invention, taken along the line 1-1 of Figure 4.

Figure 2 is a similar view, taken along the line 2-2 of Figure 4.

Figure 3 is a similar view taken along the line 3-3 of Figure 4.

Figure 4 is a horizontal section, partly broken away, of an internal combustion engine embodying our invention, taken on the line 4-4 of Figure 2.

Figure 5 is a transverse vertical section, with parts broken away, of a modified form of our invention.

Referring to the drawings, we have illustrated a vertical L-head internal combustion engine comprising the engine block 10 and oil pan 12. The engine block is cast to provide a manifold 14 extending along one side of the cylinders 16, the manifold 14 connect-

ing with an inlet opening 18 which is provided with an air cleaner 20. Extending along the side of cylinders 16 opposite the manifold 14 is a manifold 22, the manifolds 14 and 22 being connected by means of conduits 24 provided between adjacent cylinders and around the end ones. An outlet 26 is provided on one side of the casting and connects with the flexible air inlet tube 28 leading to the carburetor 30. Circumferentially arranged about the base or lower part of the wall of each cylinder adjacent the lower edge of the piston 32 when in its lowest position are a plurality of ports 34 which connect the two manifolds with the crankcase. A groove 36 extends about the inside of the base of the cylinders and connects the ports 34. A groove 38 is provided about the lower part of each cylinder and is provided with openings 40 so that oil that may splash through the ports 34 may drain back into the crankcase. Any usual or desired openings may be provided for admitting air to the crankcase, or the crankcase may be kept closed. During the operation of the engine a current of air passes from the manifold 14 to the manifold 22, part of this passing through the conduits 24 and part through the apertures 34. The relative proportions passing through these two parts may be varied at will by varying the size of the conduits 24 and the size and number of the openings 34. A current is thus maintained across the base of the cylinder and this current removes escaped combustion chamber products before they become mixed with the crankcase oil. It will be understood that the manifold 22 may be connected with the side chamber 11, if desired, and the air supply for the carburetor drawn from this chamber, if there appears to be a too high consumption of oil.

In the modification illustrated in Figure 5, the ventilating system is shown as applied to an engine comprising an engine block 50 and crankcase 52. In this construction the engine block is provided with ports 54 adjacent the base of each cylinder and arranged in continuations of the walls thereof. In this modification the manifold 22, side chamber 11, and air inlet opening 26 are all connected.

The structure otherwise conforms to the description of the principal embodiment.

We claim:

1. In an internal combustion engine including a plurality of cylinders and a crankcase, conduits located between the cylinders and open on one side to the air and on the other side connecting with engine air intake, the cylinders being provided with apertures adjacent the lower part of each piston at its lowest position and communicating with said conduits.
2. In an internal combustion engine including a plurality of cylinders and a crankcase, a manifold extending along one side of the cylinders and connected with the engine air intake, conduits located between adjacent cylinders and connected on one side with the manifold and on the other side open to the air, said cylinders being provided with apertures connecting the crankcase and the manifold.
3. In an internal combustion engine including a plurality of cylinders and a crankcase, a manifold on one side opening to the outside, a manifold on the other side connecting with the air intake, a conduit located between adjacent cylinders and connecting said manifolds, said cylinders being provided with apertures adjacent the lower part of each piston in its lowest position and connecting with said manifolds.
4. In an internal combustion engine including a plurality of cylinders and a crankcase, said cylinders having apertures adjacent the lower portion of each piston in its lowest position, conduits located between adjacent cylinders adjacent said apertures and opening on one side to the air, a manifold on the other side connecting with the conduits and apertures and connecting with the engine air intake, and means adjacent said apertures for conducting any escaped lubricant back into said crankcase.
5. In an internal combustion engine including a plurality of cylinders and a crankcase, connecting compartments adjacent the base of each cylinder and open on one side to the air and connecting on the other side with a source of suction, said cylinders being provided with openings leading from the compartments into the engine crankcase.
6. In an internal combustion engine including a plurality of cylinders and a crankcase, connecting compartments adjacent the base of each cylinder and open on one side to the air and connecting on the other side with a source of suction, said cylinders being provided with apertures connecting the compartments with the crankcase, and said engine being provided with additional openings below said apertures for conducting escaped lubricant back into said crankcase.
7. In an internal combustion engine including a plurality of cylinders and a crank-

case, connecting compartments adjacent the base of each cylinder and connecting on one side with the engine air intake and on the other open to the air, the engine being provided with circumferentially arranged openings in the walls of each cylinder connecting the compartments with the crankcase, the walls being provided with grooves on the inner side connecting said apertures.

8. An internal combustion engine including a plurality of cylinders and a crankcase, a ventilating system for the crankcase including a port for admitting air to the crankcase, and a suction passage provided with a portion extending between adjacent cylinders, a port in the cylinder wall establishing communication between the crankcase and said passage, and means for applying suction to said passage.

9. An internal combustion engine having a cylinder and a crankcase, said cylinder being provided with opposed apertures in the wall thereof adjacent the crankcase, and means for passing a stream of air through said apertures across the base of the cylinder to remove vapors from the cylinder prior to their admission to the crankcase.

10. An internal combustion engine having a cylinder and a crankcase, the walls of said cylinder being apertured at the end adjacent the crankcase, means for applying suction to said apertures to remove vapors from the crankcase, said cylinder being provided with an annular trough about its base adapted to receive oil passing outwardly through said apertures, and a port connecting said trough with the crankcase to return oil thereto.

In testimony whereof we affix our signatures.

HERBERT C. M. STEVENS.
